UNITED STATES PATENT OFFICE

ALDER F. CONNERY, OF BROOKLYN, NEW YORK, ASSIGNOR TO POSTAL TELEGRAPH-CABLE COMPANY, OF NEW YORK, N. Y., A CORPORATION OF CONNECTICUT

TELEGRAPH EXCHANGE SYSTEM

Application filed January 4, 1928. Serial No. 244,393.

This invention relates to printing telegraphy and particularly to printing telegraph exchange systems used in connection with printing telegraph apparatus of the well known start-stop type.

Printing telegraph machines of the start-stop type are well known in the art and are frequently used for the purpose of exchanging messages between a main telegraph office

10 and a branch telegraph or customer's office.

When only a few circuits are to be considered it is practicable to have each machine at the main office permanently connected to a corresponding machine at a branch office. This 15 arrangement necessitates as many machines at the main office as there are machines at the branch offices. When a large number of circuits are involved it is uneconomical and inconvenient to have so many machines at the 20 main office and it is desirable to concentrate the operation at the main office on a few machines and provide switching means for connecting any one of the branch office machines to an idle machine at the main office.

25 The arrangement heretofore used for accomplishing this purpose has been similar to that in use on the widely used Morse telegraph system. One objection to the Morse telegraph switching arrangement is that it 30 does not furnish a means of stopping the driving motor of the branch office machine and thereby eliminate wear and noise when not in use. A further objection is that it is possible for the operator at the branch office to cause 35 loss or delay to messages by sending them to the "wind". By this is meant the transmission of signals over a line to which no machine is connected at the main office.

The object of my invention is to overcome 40 the foregoing objections to the Morse telegraph system. I accomplish this object by causing the branch office machine to be inoperative except when it is properly connected to a main office machine and also arranging to have the driving motors on both 45 main and branch machines operate only when the machines are in use.

Referring to the drawings, Fig. 1 is a diagram of the electrical circuits of this invention. The drawing shows only one branch

office machine and one main office machine, but it should be understood that there will be a plurality of branch office machines which may be connected to any one of one or more main office machines. Fig. 2 shows how this 55 invention may be used in connection with multiple pin jacks at the main office. In the drawings like parts are represented by like numerals.

I will now proceed to describe my invention. 60

Referring to Fig. 1. The operating magnet of the branch office printer is shown at 1. The transmitting keyboard contacts of the branch office machine are shown at 2. At 3 is shown a non-polarized or neutral relay whose winding may become short circuited by the contacts of 4 which is a polarized relay. Relay 4 is equipped with a biasing spring and is connected in the line so that when either positive current or no current is supplied from the main office its contacts keep the windings of relay 3 shunted out. The transmission of messages is accomplished by making and breaking the positive line current supplied 70 from the main office and under these conditions relay 3 is unoperated because its windings are short-circuited and the current to driving motor 5 is therefore uninterrupted. When it is desired to stop motor 5 negative 75 current is supplied from the main office. Operation of polarized relay 4 removes the shunt from relay 3 which becomes energized and interrupts the current to driving motor 5. Negative current is normally supplied from the main office when the branch office machine is not in use. The line relay at the main office is shown at 6, the line jack at 7 and the indicator lamp at 8. The indicator lamp is illuminated when the branch office wishes to secure 80 a connection with a main office machine. The pin plug 9 is associated with the main office machine. The indicator lamps 10 and 11 indicate when the main office operator is not busy. The lamp 10 appears on the shelf of the switchboard and is for the purpose of informing the switchboard operator whether or not the main office operator is busy. Lamp 11 is located at the main office operator's position 85 and its purpose is to give the operator an in- 90

dication that the non-busy signal is appearing at the switchboard on lamp 10. In series with the pin plug 9 is the operating magnet 12 of the main office printer, the transmitting keyboard contacts 13 and relay 14. The jacks, relays, etc., in Fig. 1 have been shown in the idle position. Assume now that the branch office operator desires to send to the main office. The branch office operator depresses key 15 for a moment and thereby opens the line. This de-energizes winding 16 of relay 6 which falls back. Relay tongue 17 in falling back shunts out winding 16 and prevents it being energized when the line circuit recloses. 10

15 Relay tongue 18 completes the circuit through lamp 8 which is illuminated until the switchboard attendant responds and inserts a plug and cord thereby connecting the branch office with a machine at the main office.

20 The insertion of plug 9 in jack 7 will open the lamp circuit 8. The circuit from negative battery 19 will be opened and the positive line battery 20 will now be supplied through relay winding 21 through sleeve of jack 7 and 25 plug 9 through 12, 13 and 14, through tip of plug 9 and jack 7 and through the line to the branch office machine. The positive current now supplied from the main office starts the branch office machine as previously explained. 30 Relay 6 is energized and operates in response to the line signals. The insertion of plug 9 in jack 7 also starts the main office machine in the following manner. When the plug is inserted in the jack, relay 14 pulls up 35 and causes a momentary current impulse through condenser 26 to flow through winding 22 of relay 23. Relay 23 locks up through its winding 24 and extinguishes lamps 10 and 11, and at the same time through its left tongue and contact closes the circuit to motor 25 which starts. Messages may now be exchanged by the main and branch office operators.

40 The main office operator will initiate the 45 termination of the connection by momentarily depressing key 28 which unlocks relay 23 which falls back and stops motor 25 and illuminates lamps 10 and 11. The switchboard attendant observes that lamp 10 is illuminated and removes the plug from the line jack. The removal of the plug causes negative battery to be applied to the line which stops the motor of the branch office machine. A situation might occur, however, in which 50 the main office operator made the erroneous conclusion that the branch office operator had no further messages to send and therefore depressed key 28 which stopped the main office printer motor and illuminated the lamp 10 55 at the switchboard. The branch office operator would be unaware that the main office machine had been stopped and might decide to send some more messages. Provided the branch office operator resumes sending before 60 the cord has been pulled down at the board

no loss of messages can occur because the first signal sent from the branch office will cause relay 14 to operate and generate an impulse which will again lock up relay 23, start the motor and extinguish lamp 10 at the switchboard. It would be impossible of course for the branch office operator to transmit after the cord and plug had been pulled out of the line jack at the switchboard since the branch machine would be completely stopped by reason of the reversed current from the main office. In this case it would be necessary for the branch office operator to again signal the switchboard operator by depressing key 15. 70 75

In some installations of this system it might be desirable to eliminate the need for the switchboard operator and permit the main office printer operators to do their own switching. If there are several operators at the main office they will not all have easy access to line jack 7 so it will be necessary to multiple the line jacks and lamps so as to appear in different locations where one of them may be reached conveniently by any operator. Fig. 2 shows how this may be done with three 80 line jacks and lamps. It will be readily seen that this scheme will permit using as many line jacks and lamps in multiple as required. 90 95

Although the invention has been disclosed and described in conjunction with a particular type of system it is, of course, obvious that various departures may be made without departing from the spirit and scope of the present invention.

I claim:

1. In a printing telegraph exchange system, a main station, a plurality of branch stations, means for establishing a printing telegraph circuit between said main station and any one of said branch stations, means at said main station for rendering inoperative the main station printing telegraph apparatus and means at said main station responsive to signalling impulses from the branch station to render operative said main station printing telegraph apparatus. 100 105 110

2. In a printing telegraph switching system, a plurality of branch telegraph stations each provided with a receiving printer and transmitter, a line conductor connected with each branch telegraph station for the transmission of messages, means at the central telegraph office operated from the branch station over said line conductor for indicating when the branch station requires a connection with a central office printer and means responsive to said connection for controlling the driving motor at the branch telegraph station, control of said driving motor being effected over said line conductor by the change in polarity of line potential, means for rendering the central office printing telegraph machine inoperative and means automatically controlled by the receipt of printer signals to render said 115 120 125 130

central office printing telegraph machine operative.

3. A printing telegraph system comprising, a plurality of subscribers' lines terminating at a central office, cord circuits at the central office for the connection of any central office printing telegraph machine with any of said subscribers' lines, manually operated means at the central office for rendering any of said central office machines inoperative, said central office machines being made operative when a make signal flows through the cord circuit associated with said central office machine and indicator means operating while said central office machine is inoperative.

10 4. A printing telegraph system comprising, a plurality of subscribers' lines, each of said lines normally terminating in one or more pin jacks at the central office, relay means at said central office associated with each of said lines, each of said relay means having two windings and two sets of contacts, one of said windings being in series with the positive line current supply and the other winding being in series with the negative line current supply, one pair of said contacts being arranged to shunt one of said windings and the other pair arranged to operate an indicator when the said relay means is de-energized, a pressure key in each of said lines for de-energizing said relay, motor control means responsive to change in polarity of line current for rendering subscribers' machines inoperative.

15 5. In a communication system, a main station, a plurality of branch stations, means for establishing a communication circuit between said main station and any one of said branch stations, means at said main station for rendering inoperative the main station receiving and transmitting apparatus and means at said main station responsive to signaling impulses from the branch station to render operative said main station printer.

20 6. In a printing telegraph system comprising a plurality of printing telegraph subscribers' lines terminating at a central office, manually controllable cord circuits at the central office for connection of any of said subscribers' lines with any central office printing telegraph machine, means responsive to said connection for changing the polarity of the line current, and motor controlled means at the subscribers' office responsive to said 25 change in polarity of line current.

25 7. In a printing telegraph exchange system, a main station, a plurality of branch stations, means comprising a single line conductor for establishing a printing telegraph circuit between said main station and any one of the branch stations, means at the said main station for rendering inoperative the main station printing telegraph apparatus, and means at said main station responsive to signaling impulses from the branch station to

render operative said main station printing telegraph apparatus.

30 8. In a communication system, a main station, a plurality of branch stations, means comprising a single line conductor for establishing the communication circuit between said main station and any one of said branch stations, means at said main station for rendering inoperative the main station receiving and transmitting apparatus and means at 35 said main station responsive to signaling impulses from the branch station to render operative said main station printer.

ALDER F. CONNERY.

DISCLAIMER

1,773,952.—*Alder F. Connery*, Brooklyn, N. Y. TELEGRAPH EXCHANGE SYSTEM.
Patent dated August 26, 1930. Disclaimer filed February 1, 1935, by the
assignee, *Postal Telegraph-Cable Company*.

Hereby enters this disclaimer to that part of claim 6 which is in the following words, to wit:

“In a printing telegraph system comprising a plurality of printing telegraph subscribers' lines terminating at a central office, manually controllable cord circuits at the central office for connection of any of said subscribers' lines with any central office printing telegraph machine, means responsive to said connection for changing the polarity of the line current, and motor controlled means at the subscribers' office responsive to said change in polarity of line current.”
